UNITED STATES PATENT OFFICE.

ARTHUR TREVOR DAWSON AND LOUIS SILVERMAN, OF LONDON, ENGLAND,
ASSIGNORS TO THE VICKERS, SONS & MAXIM, LIMITED, OF SAME PLACE.

FIRING MECHANISM FOR AUTOMATIC QUICK-FIRING GUNS.

SPECIFICATION forming part of Letters Patent No. 662,256, dated November 20, 1900.

Application filed July 9, 1900. Serial No. 23,018. (No model.)

To all whom it may concern:

Be it known that we, ARTHUR TREVOR DAWSON, late lieutenant of royal navy, and LOUIS SILVERMAN, engineer, subjects of the Queen of Great Britain, residing at 32 Victoria street, Westminster, London, England, have invented certain new and useful Improvements in Firing Mechanism for Automatic Quick-Firing Guns, of which the following is a specification.

This invention relates to the firing mechanism of automatic and other guns, and has for its object to provide such mechanism with means whereby the trigger or similar device employed for firing the gun is so controlled that only single shots can be fired—that is to say, the trigger has to be pulled for each discharge. Preferably we also employ in connection with said controlling means a safety contrivance which when desired can be adjusted to render the gun incapable of being fired by the trigger.

According to our invention we employ a pivoted or hinged catch having at one end a nose and at the other end a tail, the said catch being carried by a lever or similar device for actuating the firing-sear. The nose is adapted to engage with a shoulder or recess formed on or in a sliding bar constituting a portion of the trigger mechanism, a spring being provided for causing the said nose to normally occupy this position. The aforesaid tail of the catch lies adjacent to a cam-piece carried by some stationary part of the gun. This cam-piece occupies such a position relatively to the said tail that when the trigger is pulled to fire the gun the said lever carrying the catch will be shifted and will bring the tail of the catch against the said cam-piece, so that as the trigger completes its movement on being pulled the catch will thereby be caused to turn about its pivot, and thus bring its nose out of engagement with the shoulder or recess of the trigger-bar. Prior to this disengagement, however, the firing-sear becomes actuated by the said lever carrying the catch and fires the gun. When the disengagement occurs, the aforesaid spring immediately acts to return the said lever and catch to their original position but with the nose of the catch

lying above and in advance of the shoulder or recess of the trigger. Therefore in order to again fire the gun it is necessary to release the trigger and permit the same to return to its original position, so that the recess or shoulder of the trigger will occupy a correct position for the reengagement of the said nose therewith, this reengagement taking place under the action of the said spring. On again pulling the trigger the gun will be discharged, as before explained.

The aforesaid cam-piece is preferably provided with a movable lug which can be caused to lie in the path of the said lever carrying the catch by operation of an external thumb-piece. When the lug is in this position, it acts to prevent the operation of the lever and catch and the pulling of the trigger. In other words, it keeps the mechanism in a safety position.

It will be understood that the construction and arrangement of the pivoted lever carrying the catch may be varied in accordance with the class of gun to which our improved firing mechanism is to be applied.

In the accompanying drawings, which show our improvements applied to a three-pounder automatic quick-firing gun, Figure 1 is a sectional elevation showing the position of the parts prior to the pulling of the trigger to fire the gun. Fig. 2 is a similar elevation showing the position of the parts when the trigger has been almost completely pulled, and Fig. 3 is another similar elevation showing the position of the parts when the trigger has been completely pulled and the gun fired. Fig. 4 is a detail sectional plan of the cam-piece hereinafter more fully described.

A is the pivoted or hinge catch; B, the lever carrying the same; C, a lever forming part of the firing-sear; D, the sliding bar, forming part of the trigger, and E the cam-piece. The aforesaid lever B is of bell-crank formation and is pivotally mounted within the gun-casing at point b in such a manner that one of its limbs normally lies in an approximately horizontal position and the other in an approximately vertical position. The extremity of the horizontal limb is provided with a lateral stub b', which projects through

a slot b^2 and lies immediately above the free end of the lever C, which is mounted on the same axle as the firing-sear. The said sear is of the ordinary well-known construction 5 and is adapted to fire the gun when the free end of said lever C is fully depressed by the aforesaid stud b' on the bell-crank lever B. The aforesaid catch A is pivoted at b^x to the lower end of the vertical member of the bell- 10 crank lever and is formed at one end with the nose a and at the opposite end with the tail a' . d is the shoulder or recess with which the sliding portion D of the trigger is formed and with which the said nose a of the catch is 15 normally kept in engagement by the spring a^2 . The aforesaid trigger is kept in its forward position—that is to say, the position in which it is represented in Fig. 1—by a spring d' . 20 Assuming the parts to be in the position represented by Fig. 1, then when the trigger is pulled to fire the gun the tail a' of the catch A will at the proper time come against the stop-piece E and cause said catch to turn 25 about its pivot b^x until the nose a escapes from the shoulder or recess d, as represented in Fig. 2. During this movement the stud b' on the horizontal member of the bell-crank lever B has depressed the adjacent end of 30 the lever C sufficiently to trip the firing-sear and fire the gun. As soon as the nose a has escaped from the shoulder or recess d the spring a^2 (which has been previously stretched by the movement of the vertical 35 member of the bell-crank lever) will react and pull the catch, as well as the bell-crank lever, into the position represented in Fig. 3—that is to say, the nose a of the catch will then lie in advance of the recess d of the 40 trigger. In this position it will be obvious that the gun cannot again be fired until the trigger has been released and permitted to resume its normal position (represented in Fig. 1) under the action of the spring d' . As 45 the said trigger resumes this position the nose a reengages with the shoulder or recess d under the action of the spring a^2 . The parts having resumed this position, the gun can again be fired by pulling the trigger. 50 The cam-piece E is carried by the pin e and is provided with an arm or thumb-piece e' , which projects through the case of the gun in a position to be readily actuated. e^2 is a stop-lug with which the said arm or thumb-piece 55 is furnished, such lug being so shaped that when the thumb-piece is turned into the position represented by the full lines in Fig. 4 of the drawings it will lie immediately behind the vertical member of the bell-crank 60 lever B and prevent the latter from being moved and the trigger from being pulled, thereby locking the parts in the "safety" position. By shifting said arm or thumb-piece e' into the position represented by the dotted 65 lines in Fig. 4 the said lug e^2 can be removed from the path of the said vertical member of

the bell-crank lever and the trigger can then be pulled.

What we claim is—

1. In firing mechanism for guns, the combination with the firing-sear, of a hinged catch, of means connected thereto and independent of the trigger and adapted to transmit the movement of said catch to the firing-sear, of a shoulder on the trigger adapted to engage with the said catch and of a cam-piece situated in the path of the catch and adapted to be brought into engagement with said means to prevent the movement thereof substantially as and for the purpose specified. 75

2. In firing mechanism for guns, the combination with the firing-sear, of a hinged catch, of a lever for transmitting the movement of said catch to the firing-sear, of a shoulder on the trigger adapted to engage with a nose on 80 the catch, of a spring tending to maintain this engagement, of a cam-piece situated in the path of a tail on the catch and adapted to disengage the nose from the shoulder as the trigger is pulled to fire the gun, and of a 85 spring for returning the said trigger to its normal position when released substantially as and for the purpose specified.

3. In firing mechanism for guns, the combination with the firing-sear, of a hinged catch 95 having at one end a nose and at the other end a tail, of a bell-crank lever carrying at one end the said catch and at the other end a lateral lug for operating the sear, of a sliding trigger having a shoulder for the nose of the catch to engage with, of a spring for returning the trigger to its normal position, of a spring tending to keep the nose of the said catch engaged with the shoulder of the said trigger, and of a cam-piece situated in the 100 path of the tail of the catch and adapted to coöperate therewith for the purpose of disengaging the nose from the shoulder as the trigger is pulled substantially as and for the purpose specified. 105

4. In firing mechanism for guns, the combination with the firing-sear, of a spring-controlled hinged catch having at one end a nose and at the other end a tail, of a bell-crank lever carrying at one end the said catch and 110 at the other end a lateral lug for operating the sear, of a spring-controlled sliding trigger formed with a shoulder for the said nose of the catch to engage with, of a cam-piece situated in the path of the tail of the catch, and of means for preventing the trigger from being pulled substantially as described.

5. In firing mechanism for guns, the combination with the firing-sear of a spring-controlled hinged catch having at one end a nose 115 and at the other end a tail, of a bell-crank lever carrying at one end the said catch and at the other end a lateral lug for operating the sear, of a spring-controlled sliding trigger formed with a shoulder for the said nose 120 of the catch to engage with, of a cam-piece situated in the path of the tail of the catch,

of a pivoted lug carried by said cam-piece and of means for shifting the said lug into or out of the path of the said bell-crank lever, substantially as and for the purpose specified.

6. In firing mechanism for guns, the combination with the firing-sear, of a spring-controlled hinged catch having at one end a nose and at the other end a tail, of a bell-crank lever carrying at one end the said catch and at the other end a lateral lug for operating the sear, of a spring-controlled sliding trigger formed with a shoulder for the said nose of the catch to engage with, of a cam-piece

situated in the path of the tail of the catch, 15 of a pivoted lug carried by said cam-piece and of a thumb-piece projecting through the gun-casing for shifting said lug substantially as and for the purpose specified.

In testimony whereof we have hereunto set 20 our hands, in presence of two subscribing witnesses, this 19th day of June, 1900.

ARTHUR TREVOR DAWSON.
LOUIS SILVERMAN.
